UNITED STATES PATENT OFFICE.

EMMIT G. LATTA, OF FRIENDSHIP, ASSIGNOR OF ONE-FOURTH TO PRATT & LETCHWORTH, OF BUFFALO, NEW YORK.

METALLIC HAME.

SPECIFICATION forming part of Letters Patent No. 240,735, dated April 26, 1881.

Application filed November 11, 1880. (No model.)

To all whom it may concern:

Be it known that I, EMMIT G. LATTA, of Friendship, in the county of Allegany and State of New York, have invented new and useful Improvements in Metallic Hames, of which the following is a specification, reference being had to the accompanying drawings.

The object of this invention is to produce a cheap, light, and durable hame which will fit the collar better than those now in common use, and in which the parts which are liable to become worn or broken can be easily replaced, and the parts of which are readily molded, cast, and put together.

15 My invention consists, first, of an open-back metallic hame constructed on its inner edge with a projecting flange which is adapted to fit under the rim of the collar, whereby a better fit of the hame against the collar is produced; second, of an open-back metallic hame constructed on both its inner and outer edges with projecting flanges, whereby the strength of the hame is increased and a better fit of the hame against the collar is produced; third, 20 of a metallic hame constructed on its outer side with a slot for the reception of the draft-eye; fourth, of a metallic hame constructed on its outer side with a flange having a slot formed in it for the reception of the draft-eye, 25 the flange being re-enforced around the slot to afford a firm bearing for the shank of the draft-eye; fifth, in combination with a hame provided with a slot for the reception of the draft-eye, of a draft-eye having a shank en- 30 gaging in said slot and adapted to be secured to the hame by a rivet or screw; sixth, of a metallic hame provided with sockets for the reception of the terret or rein-ring; seventh, of the particular construction of the sockets 35 40 whereby they are enabled to be cast without cores; eighth, in the combination, with a metallic hame provided with sockets for the reception of the terret or hame-ring, of a terret or hame-ring provided with a shank which is 45 adapted to be introduced into the sockets of the hame and secured therein by strengthening the shank; ninth, of a metallic open-back hame constructed with a series of projections 50 on its inner rear side to receive an adjustable hame-strap loop; tenth, in combination with

a metallic open-back hame constructed with a series of projections on its inner side, of a hame-strap loop provided with a tongue or projection adapted to engage between the projections of the hame, whereby the hame-strap 55 loop is held in place; eleventh, of a hame-strap loop in which the side bars are bent in opposite directions to permit the pattern to be drawn from the sand, and to facilitate the insertion of the hame-strap.

In the accompanying drawings, consisting of two sheets, Figure 1 is a rear elevation, and Fig. 2 a front elevation, of my improved hame. Fig. 3 is a fragmentary sectional elevation of the upper part of the hame on an enlarged 65 scale. Fig. 4 is a horizontal section in line 1 1, Fig. 3. Fig. 5 is a front elevation, on an enlarged scale, of that part of the hame to which the terret is attached. Fig. 6 is a rear elevation of the same. Fig. 7 is a vertical section 70 in line 2 2, Fig. 5. Fig. 8 is a detached view of the terret previous to applying it to the hame. Fig. 9 is a cross-section of the hame applied to the collar. Fig. 10 is a cross-section of the hame, showing a modified form there- 75 of. Fig. 11 is a cross-section in line 3 3, Fig. 2, on an enlarged scale. Fig. 12 is a vertical section in line 4 4, Fig. 11, on an enlarged scale. Fig. 13 is a detached view of the draft-eye. Fig. 14 is a detached view of the lower hame- 80 strap loop. Figs. 15 and 16 show modified constructions of the terret.

Like letters of reference refer to like parts in the several figures.

A represents the body of my improved hame, 85 made of semicircular or similar cross-section, with an open or depressed back, and having laterally-projecting flanges *a a'* on the inner and outer edges of the body of the hame.

B represents the upper hame-strap loop, C 90 the terret or rein-ring, D the draft-eye, and E the lower hame-strap loop.

The flanges *a a'* extend from the lower portion of the hame, where they run out into nothing, upward to a point below the terret, where 95 they also run out into nothing, and are widest near the draft-eye, as clearly shown in Figs. 1 and 2. The inner flange, *a*, is adapted to fit under the rim of the collar, and both flanges are shaped to fit snugly against the collar, 100

whereby the hame is given a firm bearing against the collar and a close fit of the parts is produced. The hame has about the same thickness of metal throughout the entire length 5 of its cross-section, as clearly shown in Fig. 9, and the flanges *a* *a'* greatly increase the strength of the hame and permit the same to be made light.

f represents several projections formed on 10 the inner rear side of the hame, at the upper portion thereof, at suitable distance apart for holding the upper hame-strap loop, *B*, in the proper position. The loop *B* is composed of a narrow portion which surrounds the hame, and 15 a wider portion through which the hame-strap is drawn.

g is a tongue or stop projecting inwardly from one of the side bars of the loop, and arranged in such manner that when the hame- 20 strap is disconnected from the loop the stop *g* will pass by the projections *f* of the hame and permit the loop to be freely raised and lowered. Upon passing the hame-strap behind the inner bar of the loop the latter is 25 drawn inward, so as to bring the stop *g* between two of the projections *f*, whereby the loop is held against vertical movement. By this means the loop *B* is readily adjusted on the hame, and secured in the desired position 30 without obstructing the outer surface of the hame by corrugations, as heretofore practiced.

h h are two sockets, formed one above the other on the outer side of the hame for the reception of the shank of the terret *C*. The 35 sockets *h* open toward each other—that is, the upper socket opens downward and the lower socket upward.

i represents an opening, formed in the rear side of each socket, *h*, and communicating with 40 the recess of the socket, so that the pattern can be drawn from the sand, thereby avoiding the use of cores.

k represents the shank of the terret, which is provided with two arms, which are adapted 45 to engage in the recesses of the sockets *h*. One of the arms of the shank *k*, preferably the upper one, is made longer than the lower arm, and bent as shown in Fig. 8, and the upper socket, *h*, is made correspondingly longer, so 50 that the upper bent end of the shank can be passed into the upper socket far enough to drop the short lower end into the lower socket. This being done, the upper bent arm of the shank is straightened out, as shown in Fig. 6, 55 whereby the terret is firmly attached to the hame.

Instead of constructing the terret *C* with a bent shank, which is straightened after its ends are inserted in the sockets, the terret 60 may be constructed of spring metal, as represented in Figs. 15 and 16, and sprung into the sockets.

The draft-eye *D* is constructed with a flat shank, *L*, which is passed through a vertical 65 slot, *l*, in the outer flange, *a'*, of the hame, and which bears against the rear side of the body of the hame. The groove or depression in the

back of the body of the hame is filled up at this point, so as to form a bearing for the flange or shank *L*. The flange *a'* is also re-enforced 70 or made thicker around the slot *l*, to afford a firm bearing for the shank of the draft-eye. *m* represents a rivet or screw whereby the shank *L* of the draft-eye is secured to the hame. When the eye has become worn by use, 75 it is readily detached by removing the rivet or screw *m*, and replaced by a new one. The shank *L* of the draft-eye rests in a depression formed in the outer flange, *a'*, of the hame, and the rivet is substantially relieved from all 80 strain in pulling on the draft-eye.

N is the eye or loop to which the holdback-ring is attached. It is preferably formed in one piece with the draft-eye, as shown, but it may be formed at the outer end of the rivet 85 *m*, by which the draft-eye is secured to the hame.

The lower hame-strap loop, *E*, has its side bars, *o*, bent or curved in opposite directions, one outward and one inward, as clearly shown, 90 whereby the pattern is enabled to be drawn from the sand, and the use of cores in casting the loop is avoided, and the shape of the loop rendered more suitable for an easy attachment of the hame-strap, since the front bars of the 95 two loops are curved in opposite directions or away from each other and permit the fingers to enter between the front bars, even when the loops are brought closely together.

The parts of my improved hame are each 100 easily molded and cast complete of malleable iron, and readily put together.

I claim as my invention—

1. A metallic hame composed of a hollow shell made **U**-shaped in cross-section, open at 105 the back and having on its inner edge a projecting flange, *a*, adapted to fit under the rim of the collar, substantially as set forth.

2. An open-back metallic hame constructed on both its inner and outer edges with projecting flanges *a* *a'*, fitting against the collar, substantially as set forth.

3. A metallic hame constructed with a slot, *l*, for the reception of a detachable draft-eye, substantially as set forth.

4. A metallic hame constructed on its outer side with a flange, *a'*, having a slot, *l*, for the reception of a detachable draft-eye, the flange being re-enforced around the slot to afford a firm bearing for the draft-eye, substantially 120 as set forth.

5. The combination, with a metallic hame having a slot, *l*, of a draft-eye provided with a shank, *L*, engaging in the slot *l*, and secured to the hame by a rivet or screw, substantially 125 as set forth.

6. A metallic hame provided with sockets *h h*, for the reception of a detachable terret, substantially as set forth.

7. A metallic hame provided with sockets *h h*, arranged one above the other and opening toward each other, and openings *i*, formed in the rear sides of the sockets and communicating with the recesses of the same, whereby the

- sockets are enabled to be cast without cores, substantially as set forth.
8. The combination, with a metallic hame provided with sockets *h h*, of a terret, C, having a shank, K, constructed with two arms, one arm being curved and adapted to be straightened after the insertion of the arms in the sockets *h h*, thereby securing the terret C to the hame, substantially as set forth.
9. A metallic open-back hame constructed with a series of projections, *f f*, on the inner side of the depression or groove in the back of the hame, substantially as set forth.
10. The combination, with a metallic open-back hame constructed with projections *f f* on its inner rear side, of a hame-strap loop, B, provided with a tongue or projection, *g g*, adapted to engage between the projections *f f* of the hame, substantially as set forth.
11. A hame-strap loop, E, having its side bars, *o o*, bent or curved in opposite directions, substantially as set forth.
